LUMINAIRE

Christopher C. Layton, San Francisco, Calif., assignor to
Filper Corporation, San Ramon, Calif., a corporation
of California

Continuation-in-part of design application Ser. No.
5,884, Feb. 20, 1967. This application Oct. 24,
1967, Ser. No. 9,141

Term of patent 14 years

(Cl. D48—31)

FIG. 1

FIG. 4

FIG. 1 is a side elevational view of a luminaire embodying my new design, the other two lateral sides and the opposite side being the same;

FIG. 2 is a top plan view thereof;

FIG. 3 is a bottom plan view thereof;

FIG. 4 is a fragmentary elevational view taken in the plane of line 4—4 of FIG. 2, the light bulb itself being indicated in broken lines, and not being part of the design;

FIG. 5 is a top plan view of the generally cylindrical prismatic refractor indicated in FIG. 1 and spaced within the outer housing of the luminaire, the top and bottom circular flanged plates indicated in FIGS. 3 and 4 being omitted.

This is a continuation-in-part of Christopher C. Layton design application Ser. No. 5,884, filed Feb. 20, 1967 for Luminaire, now abandoned.

I claim:

The ornamental design for a luminaire, substantially as shown and described.
